(57) **CLAIM**

The ornamental design for a mobile phone, as shown and described.

DESCRIPTION

1. Mobile phone
2. Mobile phone
3. Mobile phone
- 1.1 is a front view of a first embodiment of a mobile phone, showing my new design;
- 1.2 is a back view thereof;
- 1.3 is a left side view thereof;
- 1.4 is a right side view thereof;
- 1.5 is a top plan view thereof;
- 1.6 is a bottom plan view thereof;
- 1.7 is a back perspective view thereof;
- 1.8 is a front perspective view thereof;
- 2.1 is a front view of a second embodiment of a mobile phone;
- 2.2 is a back view thereof;
- 2.3 is a left side view thereof;
- 2.4 is a right side view thereof;
- 2.5 is a top plan view thereof;
- 2.6 is a bottom plan view thereof;
- 2.7 is a back perspective view thereof;
- 2.8 is a front perspective view thereof;
- 3.1 is a front view of a third embodiment of a mobile phone;
- 3.2 is a back view thereof;
- 3.3 is a left side view thereof;
- 3.4 is a right side view thereof;
- 3.5 is a top plan view thereof;
- 3.6 is a bottom plan view thereof;
- 3.7 is a back perspective view thereof; and
- 3.8 is a front perspective view thereof.

The broken lines show portions of the mobile phone that form no part of the claimed design in the embodiments in which they are shown.

1 Claim, 18 Drawing Sheets
